US0D1044501S

(12) **United States Design Patent** (10) **Patent No.:** **US D1,044,501 S**
(45) **Date of Patent:** **** Oct. 1, 2024**

(54) **PACKAGING FOR ORAL CARE DEVICE**

(71) Applicant: **Sage Products, LLC**, Cary, IL (US)

(72) Inventors: **Paul M. Fowler**, Cary, IL (US);
Ronald C. Cagle, Crystal Lake, IL (US);
Theresa L. Sebastian, Cary, IL (US);
Timothy J. Rapinchuk, Cary, IL (US);
Catherine S. Boulos, Cary, IL (US);
Abhi R. Patel, Lake Barrington, IL (US)

(73) Assignee: **Sage Products, LLC**, Cary, IL (US)

(**) Term: **15 Years**

(21) Appl. No.: **29/894,585**

(22) Filed: **Jun. 12, 2023**

Related U.S. Application Data

(62) Division of application No. 29/683,163, filed on Mar. 11, 2019, now Pat. No. Des. 988,868.

(57) **CLAIM**

We claim the ornamental design for a packaging for oral care device, as shown and described.

DESCRIPTION

FIG. 1 is a front, left perspective view of a packaging for oral care device, shown in a first environment of use;

FIG. 2 is a front, left perspective view of the packaging for oral care device of FIG. 1 with environmental structure removed;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a front, left perspective view of the packaging for oral care device of FIG. 1 shown in a second environment of use; and,

FIG. 10 is a front, left perspective view of the packaging for oral care device of FIG. 1 shown in a third environment of use.

The broken lines in FIGS. 1, 9, and 10 illustrate environmental structure and form no part of the claimed design. All other broken lines depict portions of the packaging for oral care device that form no part of the claimed design.
